COMBINED SECTIONAL ASH TRAY AND LIGHTER SET OR SIMILAR ARTICLE

James R. Reichow, St. Paul, Minn., assignor to Brown & Bigelow, St. Paul, Minn.

Application March 19, 1956, Serial No. 40,660

Term of patent 14 years

(Cl. D85—2)

FIG. 1

FIG. 3

Fig. 1 is a perspective view of a combined sectional ash tray and lighter set or similar article, showing my new design in assembled position;

Fig. 2 is a side elevational view thereof in assembled position; and

Fig. 3 is an exploded perspective view thereof with the lighter omitted for convenience in illustration.

I claim:

The ornamental design for a combined sectional ash tray and lighter set or similar article, as shown and described.
